UNITED STATES PATENT OFFICE.

BENJAMIN F. MIESSNER, OF SOUTH ORANGE, NEW JERSEY.

ELECTRON-DISCHARGE DEVICE.

Application filed May 13, 1927. Serial No. 191,195.

This invention relates to electron discharge vacuum tubes and like devices, and to an electric signal receiving system employing one or more of such tubes as rectifiers, repeaters or amplifiers; more particularly to such a system wherein sources of unsteady potential are used for energizing one or more of the vacuum tube circuits.

When sources of ordinary unsteady potential are used for energizing vacuum tubes in circuits there is a tendency to produce low frequency disturbing current variations or hum in the plate circuits of the tubes which materially interferes with the operation of the system. Such variations may arise from a number of causes.

Thus, when the plate or output circuit is energized from a direct current commutating machine, or from an ordinary alternating current rectifier and filter which filter does not effect a complete smoothing out of the rectified current, the current in the plate circuit is subject to periodic variations or ripples.

Also when the tube filament is heated by ordinary alternating, such as 60 cycle commercial current, or other unsteady current a number of effects are produced, which may contribute to a greater or less extent to the production of disturbing plate current variations. Thus during momentary recurring periods of low current, the temperature of the filament falls and the electron emission from the heated filament is momentarily reduced which tends to decrease the flow of electrons to the plate electrode.

Also when unsteady current is used for heating the filament, the variations in the difference of potential between different portions of the filament tend to cause variations in the plate current. It appears that portions of the filament which are momentarily of higher positive potentials than other portions have the effect of diverting from the plate some of the electrons emitted from the lower potential portions of the filament, thus periodically robbing the plate of some of its supply of electrons. This robbing effect increases with increase in potential difference between the different portions of the filament, and I also find that the robbing effect is greater when the high and low potential portions of the filament are spaced closer to one another than when they are spaced farther apart.

In vacuum tubes employing grids, the grid is generally connected to some point of the

filament supply circuit so as to maintain the grid at a fixed normal potential relative to some point of the filament. Thus when the grid is connected to a mid potential point 60 of the filament supply circuit, the normal potential of the grid is that of the mid point of the filament. If, when so connected, the filament is heated by alternating current all points of the filament except the mid-point 65 will vary periodically in potential with respect to the grid. When the current is flowing in one direction through the filament the grid will be positive with respect to one-half of the filament and negative with respect to 70 the other half, and when current is flowing in the opposite direction the grid will be negative with respect to the one-half and positive with respect to the other. The grid, which is thus always positive with respect to 75 half of the filament, affects electron emission from this half of the filament and tends to cause variation in the plate current in a manner quite similar to the effect which the higher potential portions of the filament have 80 on the lower potential portions of the filament, and which I have referred to above as the robbing effect. This grid effect, similarly to the robbing effect, increases with increase in potential difference between the 85 grid and the portions of the filament which are at lower potential.

I also find that among the factors or conditions which affect the degree of production of distributing variations in the plate current are the plate voltage and the grid biasing voltage. Generally the greater the plate voltage the less effective is the tendency to produce such variations. When a negative grid biasing voltage is employed, I find that an increase in the negative grid bias within limits tends to increase the hum effects; an increase in the negative grid bias being similar in its effect to the effect caused by decreasing the plate voltage.

When the plate circuit of one tube is coupled to the grid circuit of the succeeding tube, as in the case of a multi-stage amplifier, any low frequency hum variations passed on to the grid of the succeeding tube are amplified by the succeeding tube. This is particularly true when the coupling between the tubes is one designed for audio frequency because the disturbing variations, being of low frequency, are readily passed on by such a coupling to the succeeding tube. This effect is even evident when the coupling between the

tubes is designed for radio frequency, as in the case of a multi-stage radio frequency amplifier. It appears that the unsteady energizing currents in the radio frequency tube circuits have the effect of causing the high frequency signal currents received by the tube to be modulated at low frequency, and these modulated currents are readily passed on to the succeeding tubes by the high frequency couplings to be subsequently detected in the detector stage to become an audio frequency.

In my copending application, Serial No. 117,076, filed June 19, 1926, I described the effect which certain of the above mentioned conditions have in the production of hum. I pointed out that the effect caused by variations in filament voltage, which I term the robbing effect, and the effect caused by variations of temperature of the filament, which I term temperature effect, occur at a frequency double that of the frequency of the current in the filament, and these two effects oppose one another in phase relation in such a way that the net effect in the plate circuit due to the combined action of temperature effect and robbing effect may be much less in amount than either the temperature effect or the robbing effect alone. In said application I disclose a multi-stage signal receiving system and, as a means for reducing disturbing variations in the plate circuits, I disclose a three-electrode vacuum tube of special construction which I employ in certain stages of amplification.

In the present invention, which has for its object the reduction of hum, I also make use of a special vacuum tube which is of novel and improved construction, particularly with respect to the form and dimensions of its filament.

In the preferred embodiment of my improved tube for the common use of received radio signal amplifying and repeating, and like purposes, the filament is straight and short, preferably from .75 to 1.25 inches in length. It is approximately circular in cross section with a relatively large diameter of from approximately 4.5 to 9 mils or more, and it has sufficient surface to supply enough electrons for normal operation of the tube as a repeater or amplifier when the filament is heated to a black red heat; that is to a red which is but imperfectly visible. The filament in a suitable form of my invention is a platinum-nickel wire coated with a ready electron emitting material, such as the oxides of strontium and barium. The resistance of the platinum nickel alloy, the cross sectional area and length of the filament and the heat radiating surface of the filament are such that sufficient electrical energy can be supplied to the filament to heat it to its operating temperature at a voltage considerably less than two volts.

The tube having a filament of the char-

acteristics above described is particularly adapted for use with alternating or other unsteady current in the filament. Due to the large diameter the filament has high heat inertia or heat storage capacity and as a result the temperature of the filament falls little during recurring periods of low current. The increased diameter gives greatly increased electron emitting surface and permits the tube to be operated at a very low temperature at the same time providing sufficient electron emission for operation. Operating the filament at low temperature is a distinct advantage. During periods of low current when there is not sufficient electrical energy supplied the filament to maintain its temperature the filament momentarily cools. As it cools its rate of electron emission decreases. The drop in temperature during the periods of low current is dependent on the rate upon which the filament is losing heat by radiation. As this rate is approximately proportional to the fourth power of the temperature the filament, when operated at low temperature, will lose much less heat and will drop less in temperature than the filament operated at high temperature. In point of fact, with my low temperature filament, the actual drop in temperature during periods of low current is so small that the decrease in the rate of emission is actually less than the decrease in the rate of emission of a filament operated at high temperature, and this is true in spite of the fact that in order to provide sufficient electron emission at low temperature my filament must have a much greater radiating surface than a filament designed for operation at high temperature.

The application of the necessary energy to produce the required electron emission at low voltage results in minimizing the robbing effect because no portion of the filament will at any time be of much higher potential than any other portion, and the higher positive potential portions of the filament do not divert from their normal path to the plate to any considerable extent, electrons emitted from the lower potential portions. Furthermore as the filament which I employ is straight, high and low potential portions of the filaments are located a maximum distance apart, which also minimizes the robbing effect.

I also find that I am able to reduce still further the robbing effect by a proper selection of plate and grid biasing voltages. With a higher plate voltage the high potential portions of the filament have less effect towards diverting electrons away from the plate. A negative grid bias has an effect similar to a reduction in plate voltage. That is, it increases the tendency of the high potential portions of the filament to divert electrons from the plate. With a relatively

low plate voltage therefore I use a relatively low negative grid bias and with higher plate voltage a higher negative grid bias. In practice I employ with a tube such as described 5 plate voltages of the order of 100 to 150 volts and grid biasing voltages of from -3 to -5 volts when the tube is being operated as a radio frequency or an audio frequency amplifier.

10 As previously explained, with the grid connected to a point of the alternating current filament supply circuit, there are always portions of the filament which vary periodically in potential with respect to the grid, and the normal effect of such variations in potential is to produce disturbing variations of the plate current. This tendency, as also previously explained, increases with increased amplitude of potential variations 15 between such portions of the filament and the grid. It will be apparent that heating the filament by alternating current of comparatively low voltage minimizes the disturbing variations arising from this source.

20 From the above discussion it will be seen that in my improved tube the temperature effect and the robbing effect are each reduced to a minimum. As these effects, as previously stated, oppose one another in phase relation, it will be apparent that in operating my improved tube with unsteady current in the filament the actual hum produced in the plate circuit by the conjoint action of the temperature and robbing effects will be very small.

25 In operation of this tube not only have I reduced both the temperature and robbing effects, but their values over the range of filament, grid and plate potentials at which the tube operates efficiently as a repeater are 30 so small and so nearly equal that the resulting hum in the plate circuit due to the unsteady filament heating current is practically negligible.

The use of a straight filament of short 45 length simplifies the mounting of the filament in the tube and makes the tube more economical to manufacture. As the filament is of large diameter it is strong, durable and has a relatively long life.

50 Receiving systems employing tubes with relatively thin or long filaments are particularly susceptible to the production of disturbing microphonic effects. The thin or long filaments are easily set in vibration when 55 the tube is jarred or when sound vibrations reach the tube from the loud speaker, and such vibration of the filament produces disturbing variations in the plate current which are reproduced as sound in the loud speaker 60 or telephones. To avoid this disturbing effect, it has been the practice to mount tubes on spring sockets which act as shock absorbers to prevent jars or other vibrations reaching the tube. The filament of the tube constructed 65 in accordance with the present invention,

being of large diameter and relatively short, is not easily set in vibration. The disturbing microphonic effects do not occur in systems employing such tubes, and I find that it is not necessary in such systems to employ 70 spring sockets or equivalent means for reducing the microphonic effects.

While my tube may be used as a repeater or other discharge device in systems of widely different types, I disclose its use in connection with a signal receiving system having radio and audio stages of amplification, and a detector stage, and I preferably employ my improved tube in each stage of this system. The filaments of all of these tubes are heated 75 by alternating current and the plate circuits are energized from a source of alternating current through a rectifier and filter. In addition to utilizing my improved tube, the system embodies additional means for eliminating any hum in the plate circuit of the last tube, which may result from fluctuating potentials supplied to the plate circuit by the filter, or any residual hum arising from the use of alternating current in the filaments. 80

85 Other advantages of my invention will appear from the following description taken in connection with the accompanying drawing, wherein Fig. 1 is a side elevation of a three-electrode vacuum tube showing one embodiment of my invention. Fig. 2 is an opposite side elevation of the same tube with a portion of the tube plate taken away to show the grid and filament. Fig. 3 is a top plan view of the tube. Fig. 4 is a curve diagram illustrating the results of an operating test on the tube shown in Figs. 1 to 3, the tube under test operating as an audio frequency amplifier. Fig. 5 is a curve diagram explanatory of the results obtained in the operating test of Figure 100 4; Figure 6 is a diagram showing the result of another test on the same tube, the tube being operated as a detector during this test, Figure 7 is a diagram of a multistage signal receiving system employing my improved 105 tube in each stage, and Fig. 8 is a view similar to Fig. 2 but showing a tube having two filaments connected in the supply circuit in parallel with one another.

110 Figs. 1 to 3 show one form of my improved tube particularly suitable for the power required in the amplification and repeating of radio reception with a loud speaker, in substantially its exact size and dimensions. This tube comprises a filament 10, grid 11 and plate 12. The filament 10 is straight, approximately 1 1/4 inches long, nine mils in diameter and is formed of platinum-nickel wire, coated with oxide of strontium and barium. When an alternating current of .9 effective volts is 120 applied to the terminals of the filament, the current through the filament is approximately 1.25 effective amperes, which is a normal filament current for proper operation of the tube. This current heats the filament to a 130

black red heat, that is, a dull red heat which is but imperfectly visible.

The filament is connected at its ends to leading-in wires, 15 and 16, which are sealed 5 through the glass neck of the tube, the wires 15 and 16 serving to support the filament in the position shown. The grid 11, which surrounds the filament, is a flat coil of fine wire wound on spaced vertical rods 18, the lower 10 ends of which are attached to supporting wires 19 sealed in the glass neck of the tube, one of the wires 19 extending through the neck and forming the leading-in terminal of the grid.

15 The plate 12, which is spaced from and surrounds the grid 11, is formed of two thin sheet metal side members 20 and 21, bent toward one another and joined together near their side edges. The outer edges of the members 20 20 and 21 are pinched around supporting rods 22 which are secured at their lower ends to wires 23, sealed in the glass neck of the tube, one of the wires 23 extending through the neck and forming the leading-in terminal of 25 the plate.

The tube shown in Figs. 1 to 3 has a single straight filament. In other tubes constructed by me, I have employed two or a plurality of spaced filaments mounted parallel to one 30 another in the central plane between and parallel to the side members 20 and 21 of the plate 12. These filaments have substantially the same form, dimensions and composition as the filament 10 of the tube shown in Figs. 1 35 to 3. The filaments in the modified tube are connected to the supply circuit in parallel with one another and are operated at approximately the same or a somewhat less voltage than the filament of the tube shown in Figs. 1 40 to 3. In Fig. 8 I have shown a tube of this character wherein two filaments 10^a and 10^b are each connected at their opposite ends to the respective leading-in wires 15^a and 16^a, thus connecting two filaments in parallel in 45 the supply circuit. It is readily seen that with such a two-filament tube, the electron emission distribution with respect to the surrounding grid and plate structures is greatly improved.

50 In Fig. 4 I show diagrammatically by curves the results of a comparative "hum" test made on two tubes, one of which is a tube hereinbefore described. This test shows the amount of hum produced in the plate circuit of the herein described tube when its filament is heated by a 60 cycle alternating current, and the plate and grid biasing voltages are respectively 130 and -4 volts, these being the plate and grid biasing voltages suitable 55 for efficient operation of the tube as an audio frequency amplifier. In the Figure 4 diagram, the lower row of abscissæ values represent the effective alternating current voltages applied to the terminals of the filament of the 60 tube herein described, which I term the tube

T. Ordinates represent the hum in volts, and the curve E_h represents the hum produced in the plate circuit for values of filament voltages ranging from .44 volts to .95 volts, within which range of voltage the tube T operates 70 efficiently as an amplifier.

In my copending application above referred to, I describe the results of a similar hum test made on the special tube described and shown in that application, and in Fig. 7 75 of the drawing of that application I illustrate by means of a hum curve results of the test on such tube over a range of filament voltages of 2.6 to 6. The tube in this test was operated at a plate voltage of 135 and a grid biasing voltage of -4.5 volts; these being values at which the tube operates effectively as an audio frequency amplifier. To furnish a comparison between the amount of hum produced by the tube described in my copending application, 80 which I will term the tube T', and the tube T of the present application I have reproduced in Fig. 4 of the accompanying drawing as curves E'_h and I_k on a greatly enlarged scale the hum curve E_h, and the plate current curve I_k, respectively, shown in Figure 7 of my copending application. The upper row of abscissæ values represent the effective alternating current voltage applied to the terminals of the filament of tube T'. The plate current curve for the tube T of the present application is quite similar in form and position to the plate current curve I_k shown in present Fig. 4. Under the conditions of test on the tubes T and T' both tube showed practically 90 the same amplifying ability.

A comparison of the hum curves E_h and E'_h shows that the hum produced in the plate circuit of the present tube is considerably less than the hum produced by the former tube throughout practically an entire range of filament voltage variation equal to 50% of the maximum. Both curves reach a maximum early in increasing the filament voltage, the maximum of curve E_h being considerably less than half the maximum of curve E'_h. As the filament voltages are still further increased, the hum of each tube is reduced until it reaches a minimum for each tube at approximately .725 filament volts for tube T and 4.8 volts for tube T'; the hum volts at these minima being substantially the same. Further increase in filament voltage increases the hub of both tubes, but in the case of tube T', the hum increases at a much greater rate than does the hum of tube T. Thus over practically the entire ranges of filament voltages within which ranges these tubes operate most efficiently as amplifiers, the hum voltage of tube T is considerably less than the hum voltage of tube T'. 100

This advantage is gained through the particular construction of the present tube, particularly by the use in such tube of the special filament above described. In operating the 105 tube T the filament voltage is increased 110

tube T in the manner above set forth, not only is the temperature effect and the robbing effect each reduced to a minimum, but as these two effects tend to oppose one another in phase relation, the actual hum produced in the plate circuit by the combined action of both effects is practically negligible throughout a wide range of filament voltage variation.

In Fig. 5, I illustrate how the hum effect represented by the hum voltage curve E_h of Fig. 5 may result from the combined action of the temperature effect and the robbing effect. The temperature effect is represented by the curve E_t of Fig. 5 and it will be seen that this effect reaches a maximum approximately where the filament voltage-plate current characteristic curve is steepest, that is, when a small change in the voltage of, or current in, the filament, and therefore small change in filament temperature, makes the greatest change in effective space or plate current. Beyond this point, the temperature effect decreases, becoming less as the plate current curve flattens out, which shows that even though the temperature of the filament is much higher in this region than at the steepest portion of the curve the effective change of space current with change of temperature at this flatter part of the curve is much smaller. Thus, while it is quite important to use a filament having an emissive coating, such as barium and strontium oxides, which permits of useful degrees of emission at low temperature, and to otherwise decrease the overall tendency to avoid varying the emission by temperature effects, as by the use of large mass of the filament, yet the comparatively large amount of hum as shown by the curves at points of lower temperature of filament clearly brings out that the mere resort to low temperature and large mass does not exhaust all the possibilities in the right direction. Further analyzing, Fig. 5, which shows the characteristics of a tube designed to operate with very low temperature and large mass of filament conditions, comparatively speaking from the point of view of common tube practice, makes it clear that the hum voltage E_t due to temperature effects is large, and too large even under the special conditions at a point of lower temperature to be usefully neutralized by the voltage effect; but by going to a higher temperature, where space current approaches saturation to temperature increase, the temperature effect hum becomes very small and is nicely overcome by a small voltage effect.

E_v represents the robbing effect curve and shows the hum effect due to increasing alternating potential difference across the filament terminals. The robbing effect increases with increasing alternating voltage applied to the filament, because with increased potential difference between different portions of the filament there is a greater force act-

ing on the electrons to divert them from their path to the plate. Both the temperature and robbing effects in the present tube T are much less than the corresponding effects in tube T'.

As I explained in my copending application above referred to, the temperature effect and robbing effect are opposed to one another in phase relation. If these two effects were displaced in phase by exactly 180° and the wave form of both effects were the same, the combined action of both effects would be represented by the curve E_h in Figure 5, whose ordinates are the differences between the ordinates of curves E_t and E_v . Where curves E_t and E_v intersect, that is, where the ordinates are equal, the resulting hum would be zero. As pointed out in said application due to the heat inertia of the filament the changes in temperature of the filament do not exactly coincide with changes in filament current, and as a result the temperature effect and robbing effect may not be displaced from one another exactly 180° and therefore not completely neutralize one another. Furthermore, it is probable that the wave form of the temperature effect is not exactly the same as the wave form of the robbing effect. Due to such differences in wave form and the displacement of the two effects by an amount different from 180° the theoretical hum volt curves E_h shown in Fig. 5 is changed to a curve of the form of curve E_h in Fig. 4. It is because of this difference-of-phase condition that it is often desirable to make the opposing effects small.

I have also made similar tests on the tubes T and T' as radio frequency amplifiers. The results obtained are similar to those indicated in Fig. 4 and show very much less hum for the tube T than for tube T'.

For the purpose of brevity and definiteness in setting forth the invention to be defined in the claims annexed hereto I give the following distinctive terms and definitions thereof as applied to the characteristic curves of my improved tube which are shown in Figs. 4 and 5 and hereinbefore fully described.

Emission curve.—The curve I_k in Fig. 4, which graphically shows the relation of the space current between filament and plate to the filament potential as the filament potential is altered to alter the temperature of or emission from the filament while the filament is under the influence of energizing potentials applied to the plate and grid for operation of the tube as an amplifier but irrespective of the signal variations impressed upon such potentials during operation of the tube.

Origin of emission saturation.—The point of maximum curvature at the upper bend of the emission curve, and beyond which relatively large change in filament temperature or voltage produces but small change in effective space current.

Hum curve.—The curves E_h and E'_h in Fig. 4 and E_h in Fig. 5 graphically showing the relation between amplitude of space current variations resulting from filament current and voltage variations and the average filament voltage as the filament voltage is altered when the filament is supplied with alternating current in the presence of plate and grid electrodes energized for normal 10 operation of the tube as an amplifier but irrespective of the signal variations impressed upon such potentials during operation of the tube, which curve depends upon the combination of the varying temperature and varying 15 electrical effects arising from the alternating current energization.

Hum minimum.—The region in the hum curve where the neutralization as between the varying temperature effects and the varying 20 electrical effects is maximum, which region is typified in Fig. 4, as that portion of the curve E_h included between the filament potentials 0.6 and 0.8 volts and that portion of the curve E'_h included between the filament 25 potentials 4.5 and 5.0.

It has heretofore not been practical to heat the filament of a detector tube with alternating current, because of the excessive hum produced in the plate circuit. In my co-pending application, I illustrate a multi-stage signal receiving system wherein the tube described in such application is used in the radio and audio stages of the system. In the radio and audio frequency stages the tube 35 filament is heated by alternating current. In the detector stage, to avoid the excessive hum that would be produced if the detector filament were heated by alternating current, I provide means for heating the detector tube 40 filament by direct current. The tube described in the present application may be used as a detector as well as an audio and radio frequency amplifier, and when used as a detector, its filament may be heated by alternating current without the production of any 45 appreciable hum.

In Fig. 6 I show by the curve E_h the hum in the plate circuit of the tube T when this tube is being used as a detector with its filament 50 heated by 60 cycle alternating current, and I show by the curve E'_h , the corresponding hum produced in the plate circuit of the tube T' of my copending application. Ordinates for each curve represent hum volts. The lower 55 row of abscissæ values represent the effective volts across the filament terminals of tube T ranging from .6325 volts to .8625 volts and the upper row represent the effective volts across the filament of tube T' ranging from 60 2.6 volts to 3.4 volts; these being ranges of voltage within which the respective tubes operate efficiently as detectors. The plate voltage of tube T in this test was 30 volts and its grid bias -3.0 volts, the plate voltage of 65 tube T' was 27 volts and its grid bias -4.5

volts. The action of both tubes as detectors, that is as rectifiers with incidental amplification of signal current, was about the same. When the same signal current was impressed on the grids of the two tubes, this current being such as to produce a fairly loud sound in a loud speaker associated with the plate circuits of the tubes through two stages of audio amplification, the signal volts represented by the curves E_h and E'_h were produced 70 in the plate circuits of the respective tubes T and T'.

It will be seen that the hum produced in the plate circuit of the tube T' is enormously greater than the hum in the plate circuit of tube T, and the hum of tube T' is so great in proportion to the signal volts that it completely masks the signal received. On the other hand, the hum in the plate circuit of tube T is so small in proportion to the signal 80 volts that its effect on the signal received is practically negligible.

An inspection of the curves E_h and E'_h of Fig. 6 shows that the hum for both tubes increases steadily with increase in potential 90 across the filament terminals and in this respect both curves are similar to the curve E_v of Fig. 5, which represents the robbing effect of the tube T when used as an amplifier. It will also be noted that the humps or maxima which occur at the left of curves E_h and E'_h in Fig. 4 have completely disappeared in the curves E_h and E'_h of Fig. 6. These humps, as shown by the curve E_T in Fig. 5, are caused by the 95 temperature effect. The similarity of the curves E_h and E'_h of Fig. 6 to the robbing effect curve E_v of Fig. 5, as well as the absence of the humps, indicate that in operating the tubes under the plate and grid biasing voltages which render the tubes suitable for use as detectors, the temperature effect is practically zero and the hum produced is almost entirely due to the robbing effect. The extremely small hum in the plate circuit of tube T seems therefore to be due to a large extent to the 100 low voltage at which the tube T is operated, and to its straight form of filament.

If some one portion of a vacuum tube filament were spaced considerably nearer to the plate or grid of the tube than other portions 110 of the filament, and if this closer spaced portion were subject to changes in potential due to alternating current in the filament, there would be apt to result variations in the plate current due to such unsymmetrical spacing. The construction of tube shown in Figs. 1, 2 and 8 permits an even spacing of the grid and plate from the filament, and so avoids the 115 possibility of plate current variations due to the uneven spacing of these elements. Furthermore, the filaments in these tubes are of such form and so located with respect to the grids and plates that the alternating magnetic flux produced in the neighborhood of the 120 filament, caused by the alternating filament 125

current, has small tendency to produce variations in the plate current by causing variations in the flow of electrons from the filament to the plate, an effect in phase alliance with the voltage or robbing effect.

In Fig. 7 I have shown one system in which my improved tube may be employed. In this system the filaments of all the tubes are heated by alternating current and the plate circuits are supplied with current derived from alternating current source through a rectifier and a filter.

Tubes 50 and 51 in Fig. 7 are radio frequency amplifying tubes; tube 52 is a detector and tubes 53 and 54 audio frequency amplifying tubes. At 60 is shown an antenna for collecting radio signaling energy having the primary 61 of the transformer 62 in series therewith, the antenna being grounded at 63. The secondary winding 64 of the transformer 62, cooperating with a variable condenser 66, permits tuning of the grid circuit of vacuum tube 50 to the frequency of any desired incoming signals. The second vacuum tube 51 is selectively associated with the first vacuum tube 50 through a transformer 68 and variable condenser 69. The detector tube 52 is selectively associated with the second radio frequency tube through a transformer 70 and variable condenser 71. The first audio frequency tube 53 is associated with a suitable audio frequency transformer 74 shown to have a resistance 76 connected across its secondary winding, the grid circuit of tube 53 being adjustable to connect with different points of the resistance 76 so as to control the volume of sound signals produced. The second audio frequency amplifier tube 54 is associated with the first audio frequency amplifier tube 40 through a suitable audio frequency transformer 78. A loud speaker or other suitable signal translating device 80 is energized by the highly amplified signal currents from the final amplifier 54. The loud speaker is connected between the filament and plate of the tube 54 through the capacity coupling condenser 82, the signal currents being diverted to the loud speaker through the condenser 82 by action of the choke coil 83 in the plate circuit of tube 54.

The two radio frequency stages are shown to be neutralized against oscillation production or excessive regenerative amplification caused by plate circuit reaction on the grid 55 through the internal capacity of the tube by condensers 84 and 85 connected to the grids of their respective tubes from a tap connection to the secondary windings of the transformers in the plate circuits of these tubes.

For the purpose of supplying energy to the system for amplification and detection of the signals received I show at 90 a transformer, the primary 91 of which is adapted to be supplied with alternating current from the usual house lighting system. Connection

between the primary and the supply system may be made by a flexible cord connector, 94 and a plug 95 adapted for insertion in the ordinary house lighting socket. Suitable switches 96 and 97 and fuses 98 may be included in the connection to the primary and, if desired, an adjustable tap 99 may be provided for including a greater or lesser number of turns of the primary in circuit with the supply mains. A secondary 100 of the transformer 90 supplies heating current at low voltage to the filaments of tubes 50 to 53 inclusive, these filaments being supplied in parallel from the secondary 100 as shown. For each of the tubes 50—53 I preferably employ the tube shown in Figs. 1—3, or the plural filament tube which I have described and shown in Fig. 7.

Tube 54, which is a power tube, has its filament supplied with current at somewhat higher voltage from secondary winding 101 of the transformer 90. For the power tube 54 I may employ a tube of the same general type as that shown in Figs. 1 to 3, except that its filament is somewhat longer than the filament of the tube shown in these figures and its filament is heated by current at a somewhat higher voltage. As any hum generated in tube 54 is not further amplified I may, if desired, employ for this tube any of a number of power tubes now available.

Connected across the secondary 101 is a potentiometer resistance 130, and adjustable along said resistance is a conductor tap 131. A second potentiometer resistance 133 is connected across the secondary winding 100 and this resistance is adapted to cooperate with a second adjustable tap 134. Taps 131 and 134 are connected through resistances 136 and 137 in series, resistance 136 being shunted by a condenser 140. The purpose of these resistances, taps and condenser will be explained later.

The energy for exciting the plate currents of the vacuum tubes is derived from a secondary winding 104 of the supply transformer 90, which for the ordinary characteristics of lighting supply by alternating current would be of the step-up form, say 110 volts to 450 volts. The alternating current energy from the secondary 104 is applied to a rectifier 106 shown as a two-electrode vacuum tube whose filament is heated by alternating current from another secondary winding 108 of the transformer 90. The alternating current from the winding 104 is rectified in a manner well understood in the art and applied to the terminals of the filter formed by two large capacity condensers 110 and 111 connected through a large inductance coil or choke 112, the filter acting in a well known manner to smooth out to a substantial degree half wave impulses resulting from rectification. The smoothed out rectified current is applied across the terminals of a

higher resistance 115, and I connect the final high power tube 54 across the terminals of this resistance to give the full voltage of the filter system to the plate circuit of the last tube. This voltage in one of the systems constructed by me is 450 volts. From Fig. 7 it will be seen that the plate of tube 54 is connected to the positive terminal of the filter through choke 83, and the filament return of 10 the plate circuit passes through tap 131, resistance 137 and conductor 141 to the negative side of the filter.

I connect the plate circuits of tubes 50, 51 and 53 between the negative terminal of the 15 filter system and an intermediate point 118 of the resistance 115, thus impressing on the plates of these tubes a voltage less than the full voltage of the system. In the system above referred to as constructed by me, I use 20 for the plate circuits of the tubes 50, 51 and 53, a voltage of 120. The filament return of the plate circuits of tubes 50, 51 and 53 may be traced from the tap 134, resistance 136, conductor 141 to the negative side of the filter.

The plate circuit of the detector tube 52 is also connected between the negative terminal of the filter and the intermediate point 118 of resistance 115, but in order to reduce the 30 voltage applied to the plate of the detector tube to the desired amount for proper operation of this tube, I include in the lead from the point 118 to the plate of this tube a resistance 120.

35 I preferably connect a high capacity condenser 150 between the point 118 and the negative end of the filter. This condenser acts as a shunt around the portion of the resistance 115 to the left of the point 118 to permit by-passing of high and low frequency signal currents, and also to assist condensers 111 and 112 in smoothing out the rectified current.

The grids of all the tubes are connected to 45 the negative terminal of the filter through the conductor 141 inasmuch as the plate circuit returns from the filaments of tubes 50, 51, 52 and 53 pass from potentiometer 133 through resistance 136, and thence through 50 conductor 141 to the negative side of the filter. It will be seen that the grids of these tubes have a negative biasing potential with respect to their filaments by an amount equal to the potential drop across the resistance 136; 55 this resistance being selected so as to give the desired grid biasing voltage to these tubes. By employing a drop of the potential created by the combined plate currents of tubes 50 to 53, resistance 136 may be of relatively 60 small value to give the necessary difference of potential for furnishing the required grid bias to these tubes. The resistance 136 constitutes a coupling element capable of transferring energy from the plate circuit back 65 to the grid circuit of the tubes as well as from

a succeeding tube back to a preceding tube, and is therefore an element tending to make the system unstable by regenerative effects if provision is not made for keeping these effects to practical low limits. A step toward 70 this end is accomplished by utilizing the combined plate current to create the desired difference in potential, thereby making the resistance 136 low. Also the condenser 140 of 75 large capacity shunting the resistance 136 permits high and low frequency current variations to avoid the resistance 136 by a low impedance path further reducing the coupling effects. As a further means for preventing the disturbing coupling effects referred to, I provide by-pass condensers 160, 80 which connect the tuned grid circuits of tubes 50-52 with their respective filaments, and in the case of tubes 50 and 51 I connect the tuned 85 grid circuits to the conductor 141 through high reactance or choke coils 161, which serve to exclude the high frequency grid currents from the resistance 136 and the filter circuits, and to divert them through the by-pass condensers 160.

I also employ in the plate circuits of the radio frequency amplifying tubes 50 and 51 by-pass condensers 165 and 166 respectively, which form a path of low impedance around the filter circuits for the high frequency components of the plate currents.

To permit the low frequency signal components in the plate circuit of detector tube 52, which pass through the primary of transformer 74, to avoid the resistance 120, I employ a high capacity condenser 168 connected between one terminal of the primary and the filament of tube 52. A low capacity condenser 169 connected between the plate and the filament of tube 52 furnishes a path of low impedance for the high frequency components of the plate current of tube 52.

The plate circuit return from the filament of power tube 54 passes through the potentiometer 130, 131 through resistance 137 to 110 the negative conductor 141. As the grid of tube 54 is connected to conductor 141, this grid receives a negative biasing potential equal to the potential drop across the resistance 137; resistance 137 being so selected as 115 to give the particular grid biasing voltage required by tube 54. While resistance 137 forms a coupling between the grid and plate circuits of tube 54, these circuits do not carry high frequency current and are not subject 120 to the disturbing regenerative effects which are apt to occur in the circuits of the preceding tubes, and I find that a shunting condenser for the resistance 137 is unnecessary.

Potentiometer resistances 130 and 133 and the adjustable taps 131-134 furnish a means by which I may eliminate any residual hum in the plate circuit of the final amplifier tube 54 which hum may be caused, for example, by low frequency variations or ripples in the 130

plate currents due to imperfect filtration of current supplied by the rectifier 106. By adjustment of the taps 131 and 134 the grids of tube 54 and tubes 50 to 53 respectively, may be subject to low frequency variations in potential relative to the mid points of their respective filament. Such variations impressed on the grid will be of greater amplitude as the points of contact of the taps with the resistances are farther away from the mid-points of the resistances and such variations, when the tap contacts with points at one side of the mid-point of the resistance, will be of opposite phase to the phase of such variations when the tap contacts with points at the opposite side of the mid-point of the resistance. By proper adjustment of these taps these variations of grid potential can be so controlled, both in amplitude and phase, as to effect a substantial neutralization of any residual hum which would otherwise occur in the plate circuit of the final tube 54.

While I have shown and described two tubes embodying my inventions, it will be understood that these tubes are merely typical of a number of tubes which have the advantages discussed. In these tubes I have used an electron emitting material consisting of oxide of strontium and barium. Other ready electron emitting materials are known and by a proper selection of such material it is possible to supply sufficient electron emission at a filament temperature even lower than the temperature at which I operate the tubes herein disclosed; that is, at a black red heat, and I deem a tube having a filament operated at such low temperature to be within the scope of the present invention.

This application is a continuation in part 40 of my applications Serial No. 117,076, filed June 19, 1926, and Serial No. 50,555, filed August 17, 1925.

I claim:

1. In a vacuum tube, the combination of an electron emissive filament, grid and plate; said tube having a hum curve including a region of hum minimum; said filament having an emission curve including an origin of emission saturation; said filament also having such length, resistivity and cross-section that when energized by alternating current said hum minimum occurs at a filament voltage greater than the filament voltage of said origin of emission saturation and at a filament amperage not greatly differing from said filament voltage, the temperature of said filament at said voltage being at least as low as the effective electron emission temperature of strontium oxide.

2. In a vacuum tube, the combination of an electron emissive filament, grid and plate; said tube having a hum curve including a region of hum minimum; said filament having an emission curve including an origin of emission saturation at a voltage less than

three volts; said filament also having such length, resistivity and cross-section that when energized by alternating current said hum minimum occurs at a filament voltage greater than the filament voltage of said origin of emission saturation and at a filament amperage not greatly differing from said filament voltage, the temperature of said filament at said voltage being at least as low as the effective electron emission temperature of strontium oxide.

3. In a vacuum tube, the combination of an electron emissive filament, grid and plate; said tube having a hum curve including a region of hum minimum; said filament having an emission curve including an origin of emission saturation at a voltage less than two volts; said filament also having such length, resistivity and cross-section that when energized by alternating current said hum minimum occurs at a filament voltage greater than the filament voltage of said origin of emission saturation and at a filament amperage not greatly differing from said filament voltage, the temperature of said filament at said voltage being at least as low as the effective electron emission temperature of strontium oxide.

4. In a vacuum tube, the combination of an electron emissive filament, grid and plate; said tube having a hum curve including a region of hum minimum; said filament having an emission curve including an origin of emission saturation at a voltage less than one volt; said filament also having such length, resistivity and cross-section that when energized by alternating current said hum minimum occurs at a filament voltage greater than the filament voltage of said origin of emission saturation and at a filament amperage equal to or greater than said filament voltage, the temperature of said filament at said voltage being at least as low as the effective emission temperature of strontium oxide.

5. In a vacuum tube, the combination of an electron emissive filament, grid and plate; said tube having a hum curve including a region of hum minimum; said filament having an emission curve including an origin of emission saturation; said filament also having such length, resistivity and cross-section that when energized by alternating current said hum minimum occurs at a filament voltage at least as small as the current in amperes flowing therein, which voltage is greater than the filament voltage of said origin of emission saturation, the temperature of said filament at said voltage being at least as low as the effective emission temperature of strontium oxide.

6. In a vacuum tube, the combination of an electron emissive filament, grid and plate; said tube having a hum curve including a region of hum minimum; said filament having an emission curve including an origin of emission saturation; said filament also having

such length, resistivity and cross-section that when energized by alternating current said hum minimum occurs at a filament voltage less in numerical value than the current in 5 amperes flowing through said filament which voltage is greater than the filament voltage corresponding to said origin of emission saturation, the temperature of said filament at said voltage being at least as low as the effective emission temperature of strontium oxide. 10

7. In a vacuum tube, the combination of an electron emissive filament, grid and plate, said tube having a hum curve including a region of hum minimum; said region of hum 15 minimum occurring at a filament temperature at least as low as the effective electron emissive temperature of strontium oxide; said filament having an emission curve including an origin of emission saturation; said filament having such length, resistivity and cross-section that said origin of emission saturation occurs at a filament voltage at least as small as the current in amperes flowing through said filament, at which voltage and 20 amperage the temperature of said filament is at least as low as said effective electron emission temperature. 25

8. In a vacuum tube, the combination of an electron emissive filament, grid and plate, 30 said tube having a hum curve including a region of hum minimum; said region of hum minimum occurring at a filament temperature at least as low as the effective electron emissive temperature of strontium oxide; said filament having an emission curve including an 35 origin of emission saturation; said filament having such length, resistivity and cross-section that said origin of emission saturation occurs at a filament voltage smaller than the 40 current in amperes flowing through said filament, at which voltage and amperage the temperature of said filament is at least as low as said effective electron emission temperature. 45

9. In a vacuum tube, the combination of an 50 electron emissive filament, grid and plate, said tube having a hum curve including a region of hum minimum; said region of hum minimum occurring at a filament temperature at least as low as the effective electron emissive 55 temperature of strontium oxide; said filament having an emission curve including an origin of emission saturation; said filament having such length, resistivity and cross-section that said origin of emission saturation occurs at a filament voltage lower than two 60 volts and filament amperage not greatly differing therefrom, at which voltage and amperage the temperature of said filament is at least as low as said effective electron emission temperature. 65

10. In a vacuum tube, the combination of an electron emissive filament, grid and plate, 70 said tube having a hum curve including a region of hum minimum; said region of hum minimum occurring at a filament tempera- 75

ture at least as low as the effective electron emissive temperature of strontium oxide; said filament having an emission curve including an origin of emission saturation; said filament having such length, resistivity and cross-section that said origin of emission saturation occurs at a filament voltage lower than the filament voltage of said region of hum minimum, and at an amperage exceeding the numerical value of said voltage, at 80 which voltage and amperage the temperature of said filament is at least as low as said effective electron emission temperature. 85

11. In a vacuum tube, the combination of an electron emissive filament, grid and plate, 90 said tube having a hum curve including a region of hum minimum; said region of hum minimum occurring at a filament temperature at least as low as the effective electron emissive temperature of strontium oxide; said filament having an emission curve including an origin of emission saturation; said filament having such length, resistivity and cross-section that said origin of emission saturation occurs at a filament voltage less than 95 one volt and a filament amperage greater than one ampere, at which voltage and amperage the temperature of said filament is at least as low as said effective electron emission temperature. 95

12. In a vacuum tube, the combination of an electron emissive filament, grid and plate, 100 said tube having a hum curve including a region of hum minimum; said region of hum minimum occurring at a filament voltage at least as low as the filament voltage corresponding to the effective electron emissive temperature of strontium oxide; said filament having an emission curve including an 105 origin of emission saturation; said filament having such length, resistivity and cross-section that said origin of emission saturation occurs at a filament voltage at which said filament is heated to temperature not greater than said effective electron emissive temperature and at which the current in amperes flowing through said filament is at least as great as said filament voltage. 110

13. In a vacuum tube, the combination of an electron emissive filament, grid and plate, 115 said tube having a hum curve including a region of hum minimum; said region of hum minimum occurring at a filament temperature at least as low as the effective electron emissive temperature of strontium oxide; 120 said filament having an emission curve including an origin of emission saturation; said filament having such length, resistivity and cross-section that said origin of emission saturation occurs at a filament voltage at which 125 the current in amperes flowing through said filament is greater than said voltage and at which the temperature of said filament renders it imperfectly visible. 130

14. In a vacuum tube, the combination of

an electron emission filament, grid and plate; said tube having a hum curve including a relatively broad region of hum minimum; said region of hum minimum occurring at a filament temperature at least as low as the effective electron emissive temperature of strontium oxide; said filament having an emission curve including an origin of emission saturation; said filament having such length, resistivity and cross-section that said origin of emission saturation occurs below the filament voltage corresponding to said region of hum minimum and the ratio of the difference in potential between any two points of said filament, measured in volts, to the distance apart of said points, measured in inches is less than unity and the operating voltage of said filament does not exceed the current in amperes flowing through said filament.

15. In a vacuum tube, the combination of an electron emissive filament, grid and

plate; said tube having a hum curve including a relatively broad region of hum minimum; said region of hum minimum occurring at a filament temperature at least as low as the effective electron emissive temperature of strontium oxide; said filament having an emission curve including an origin of emission saturation; said filament having such length, resistivity and cross-section that said origin of emission saturation occurs at a voltage below the filament voltage corresponding to said region of hum minimum and the ratio of the difference in potential between any two points of said filament, measured in volts, to the distance apart of said points, measured in inches is less than unity and the operating potential across said filament is less than the current in amperes flowing through said filament.

20. In testimony whereof I hereunto affix my signature.

BENJAMIN F. MIESSNER.
